UNITED STATES PATENT OFFICE.

EDMUND F. HARTSHORN, OF EAST NEWARK, NEW JERSEY, ASSIGNOR TO STEWART HARTSHORN COMPANY, OF EAST NEWARK, NEW JERSEY, A CORPORATION OF NEW JERSEY.

FASTENER.

979,853.

Specification of Letters Patent. Patented Dec. 27, 1910.

Application filed January 27, 1908. Serial No. 412,800.

To all whom it may concern:

Be it known that I, EDMUND F. HARTSHORN, a citizen of the United States, and a resident of the borough of East Newark, 5 county of Hudson, and State of New Jersey, have invented a new and useful Fastener, of which the following is a specification.

The object I have in view is the production of a fastener for the attachment of devices to a metallic or other base or foundation, such base or foundation being of such a character that the front only is accessible and the back is inaccessible.

The invention is particularly adaptable to 15 the attachment of shade roller brackets to metallic window frames, such metallic window frames being ordinarily made of too thin material to permit a tapped opening to be formed, and so made that the back of 20 the frame is inaccessible.

Further objects are to produce a device which may be used upon bases of varying thicknesses, which, when in place, will be substantially flush with the supported object 25 or base of the supported object, which will be cheap and simple to manufacture, and which may be applied with the use of a few tools.

Other objects will be apparent from an 30 examination of the following specification and accompanying drawings, considered together or separately.

I attain these objects by the devices illustrated in the accompanying drawings.

Figure 1 is a side view partly in section of a shade roller bracket, and a support embodying my invention. Fig. 2 is a plan view of the bracket shown in Fig. 1, the screws being a section. Fig. 3 is a view showing a 40 modification of my invention. Fig. 4 is a similar view showing another modification. Fig. 5 is a similar view showing another modification. Fig. 6 is a perspective view of a nut embodying my invention. Fig. 7 is a 45 perspective view of a sleeve embodying my invention. Fig. 8 is a detail view of a sleeve embodying my invention, such sleeve showing a modified embodiment of my invention. Figs. 9 and 10 are detail views of still another modification.

In all of the views like parts are designated by the same reference characters.

In carrying out my invention, I provide a screw 1 having an enlarged head 2, such

head being provided with a kerf for the application of a screw driver. A sleeve 3, shown in Fig. 7, has a head which surrounds the screw and enters an opening 4 in the base of the shade roller bracket 5 or other device which is to be supported. The sleeve also 60 passes through an opening 6 in the plate 7, which plate may be a portion of the wall, window frame or any other supporting media to which a device is to be secured by my improved fastener. The thickness of the 65 plate 7 is less than the length of the sleeve. The sleeve is provided with a plurality of longitudinal cuts or slots 8, which slots taper from one end of the sleeve toward the other. These slots produce a plurality of 70 tapering fingers or legs 9, such fingers or legs ending in points 10. The inside surface of the end of each of the legs adjacent to the point is inclined at 11, such inclination extending from the inner wall to the outer 75 wall of the sleeve. The other end of the sleeve is provided with a lug or lugs 12, which are adapted to enter a slot or slots 13, formed in the openings 4, such lugs and slots being for the purpose of preventing the 80 sleeve rotating, and also for the purpose of preventing the sleeve entirely passing through the opening 6. The sleeve 3 is tubular in shape and is of the size to permit the screw 1 to turn freely within it. It is 85 made of some material sufficiently ductile to permit the fingers or legs 9 to be bent without breaking.

In connection with the screw and sleeve is employed a nut 14. This nut is provided 90 with a perforated body portion internally screw-threaded and adapted to surround and engage with the threads of the screw. It is also provided with one or more fingers or projections 15, which fingers or projections are preferably pointed. Preferably there are as many fingers on the nut as there are fingers or legs upon the sleeve, the fingers on the nut being adapted to enter the spaces between the fingers or legs of the 100 sleeve. The spaces between the fingers 15 are sufficiently wide to accommodate the points 10 of the sleeve fingers when the latter are caused to engage between the fingers 15. The wall of the body of the nut at the 105 base of the fingers is inclined at 16, such inclination being preferably at the same angle as the inclination on the sleeve at 11. The

external diameter of the nut is greater than the internal diameter of the sleeve. The nut and sleeve are no larger than the openings 4 and 6, hence it is possible to introduce the screw with the sleeve and nut in place, as shown in the upper part of Fig. 1, first through the opening 4 and then through the opening 6. In use, the parts are assembled, as shown in the upper part of Fig. 1, the fingers 15 on the nut lying between the fingers 9 on the sleeve. The device comprising the screw, sleeve and nut, is now introduced through the opening 4 and the opening 6 from the front of the plate, the lug 12 entering the slot 13 and preventing the sleeve from moving any farther into the opening. The screw 1 is now rotated by means of a screw-driver. The sleeve 3 is prevented from rotating by the engagement of the lug 12 with the slot 13. The nut 14 will be given a partial rotation until its fingers 15 engage with the fingers or legs 9 of the sleeve. The nut is now gradually forced toward the base of the sleeve, causing the points 10 and inclinations 11 to engage with the inclinations 16 at the bases of the fingers 15. Further rotation of the screw will force the nut up in between the fingers or legs 9, and as the nut is larger than the bore of the sleeve, it will separate the legs and bend them outward, thus distorting the sleeve. The nut is screwed in until it can be screwed no farther, and will then bear against the turned out legs 9. The parts will now assume the position shown in the bottom of Fig. 1, the legs or fingers 9 being separated and bent outward, forming a species of hollow rivet in which the legs constitute the expanded portion and rigidly hold the sleeve in position within the plate 7 against the back or in contact with the opening 6.

The device may be modified in many ways. In place of the form of sleeve illustrated in Fig. 1, a tube 17 of lead or other relatively soft material, made without the fingers or slots, may be used. This may be introduced in the position shown in the bottom of Fig. 3. When the nut, which may be the same as that described, is screwed into contact with this tube, it will compress it longitudinally, distorting it, and making it assume the shape substantially as shown in the upper part of Fig. 3, the expansion of the tube taking the place of the bending apart of the fingers or legs 9.

In place of the nut, shown in Figs. 1 and 3, a nut formed of a coil of wire 18, such as shown in Fig. 4, may be employed. This coil of wire will surround the screw 1 and engage with its threads; the engagement of the wire with the inside of the fingers or legs 9 will prevent rotation of the coil, but by the action of the screw will separate the legs, as shown at the bottom of Fig. 4.

Fig. 1 shows the applicability of my invention to a plate 7 of considerable thickness.

Figs. 3, 4 and 5 show the application of the invention to a plate which is much 70 thinner.

In Fig. 5 is shown the applicability of the device illustrated in Fig. 1 to a thin plate in which the openings 6 have been made by 75 punching. The bur 19, formed by the punch, in no way prevents the effective holding action caused by the separation of the fingers or legs 9.

Fig. 7 shows one form of sleeve in which the lugs 12 are formed integral with one 80 edge of the sleeve.

Fig. 8 shows a modification in which but one lug is used, such lug being struck out from the material of which the sleeve is made.

Figs. 9 and 10 show a modified embodiment of the invention, in which a taper screw 20 is employed in conjunction with a split nut 21; such split nut is shown as being formed of three parts, but not having the 90 same fingers as the nut already described. The parts of the split nut are adapted to be assembled around the screw 20, and with the projections 22 lying within the fingers or legs 9. When the screw 20 is rotated, the 95 nut is drawn in the direction toward the head of the screw and is caused to separate owing to the shape of the screw. In this form of device the inclinations 11 and 16 need not be used.

An important feature of my invention is that the device does not project beyond the object fastened to any material extent. The head of the screw is the only part that projects; all the other portions of the device 105 lying within or beyond the plate. This is an important advantage in connection with shade brackets, as it permits the utilization of brackets of substantially the same shape and size as are now on the market. Any 110 projection beyond the base of the bracket would seriously interfere with the operation of the shade roller, which projections are not present in devices made in accordance with my invention.

It is to be noted that in the structure employing the sleeve with legs, the unslotted portion of the sleeve, measured from the base of the legs to the base of the lugs 12, is not greater than the thickness of the thinnest plate to which the device is to be secured. This will always insure the proper separation of the legs by the engagement with them of the nut.

My device may be applied by unskilled labor and without danger of its being improperly applied. The fastener will secure a window shade bracket to a metallic window frame without any possibility of the bracket becoming loose and without any 125 130 135

danger of the workman putting it on improperly. It is only essential that the holes in the window frame be properly located. It is to be understood that the screw may be removed whenever it is necessary to remove the bracket or other device which is secured to the plate. The screw may be returned in position or the entire fastener may be removed by destroying it or by introducing an instrument through the sleeve to bend back the sleeve legs to their first position.

In accordance with the provisions of the patent statutes, I have described the principle of my invention, together with the apparatus which I now consider to represent the best embodiment thereof, but I desire to have it understood that the apparatus shown is merely illustrative and that the invention can be carried out in other ways.

Having now described my invention, what I claim as new and desire to secure by Letters Patent, is—

1. The combination of a plate having a hole therein and a notch in the wall of said hole, and an expansible bolt for securing said plate to a support comprising a screw, a sleeve having a head through which said screw freely passes and a lug on said head

adapted to engage the notch in the hole in said plate and having tapering fingers extending at right angles from said head, and a nut on said screw having a body portion and pointed projections extending from said body portion at right angles thereto and between the fingers on said sleeve, whereby when said screw is rotated and said nut is drawn toward said sleeve, the fingers of said sleeve are forced outwardly over the body of said nut.

2. A fastener which comprises a screw, a sleeve and a nut, said sleeve surrounding the screw, and having a lug to prevent rotation, and having tapering fingers with tapering slots between the fingers and inclined ends, said nut having tapering projections, the wall of the body of the nut at the base of the projections being inclined and adapted to engage with the inclined ends of the fingers.

This specification signed and witnessed this 24th day of January, 1908.

EDMUND F. HARTSHORN.
